CLAIM

The ornamental design for a rotator, as shown and described.

DESCRIPTION

FIG. 1 is a right, front perspective view showing our new design for a rotator,

FIG. 2 is a left, front perspective view thereof,
FIG. 3 is a front view thereof, a rear view being a mirror image thereof,

FIG. 4 is a right side view thereof,
FIG. 5 is a left side view thereof,
FIG. 6 is a top view thereof; and,
FIG. 7 is a bottom view thereof.

In the drawings, the broken lines depict environmental subject matter only and form no part of the claimed design.

1 Claim, 7 Drawing Sheets
